ADELMER M. BATES, OF CHICAGO, ILLINOIS, ASSIGNOR TO BATES VALVE BAG COMPANY, OF CHICAGO, ILLINOIS, A CORPORATION OF WEST VIRGINIA.

PROCESS OF MAKING AND FILLING BAGS.

1,353,210.

Specification of Letters Patent. Patented Sept. 21, 1920.

Application filed March 27, 1919. Serial No. 285,695.

To all whom it may concern:

Be it known that I, ADELMER M. BATES, a citizen of the United States, residing at Chicago, in the county of Cook and State of Illinois, have invented a certain new and useful Improvement in Processes of Making and Filling Bags, of which the following is a specification.

My invention relates to a method or process of making and filling bags of material from a continuous roll of fabric. It is illustrated diagrammatically in the accompanying drawings where I have shown, however, diagrammatically, a mechanism which might 10 be manipulated to carry out my method. It will, however, be recognized that the method might be carried out by totally different machines or without any at all, except such devices as are necessary to support the bag 15 of material from time to time.

Figure 1 is an elevation of the upper portion of the apparatus for carrying out my process and, Fig. 2 is an elevation of the lower part of said apparatus. Like 20 parts are indicated by the same letters in each of the drawings.

Referring to the drawing, A is a hopper with its supply of material. B is a receptacle holding a measured or weighted 25 charge. C is a filling funnel and D is a filling tube depending therefrom and suitably mounted or supported. E is an outer or larger tube which incloses the filling tube. F is a roll of fabric fed forward or upwardly by feeding rolls G, one on each side 30 of the tube E. Of course, the feeding forward of the tube or fabric could be accomplished in any desired manner. G¹ is a sewing and clamping apparatus shown 35 merely in diagram but intended to draw the fabric around the tube E, form it into a tube and stretch the edges. G² G² are rolls properly positioned and adapted to draw the tube downwardly between the feed tube 40 and the outer tube. From this point the tube passes downwardly and it may be puckered or gathered as at G³. The tube is now flattened out in any desired manner by hand or otherwise so as to assume the flat shape 45 indicated at J and at this flattened portion it may be clamped as at J¹ or at J² or at both places. The idea is to stretch the tube so as to bring its sides into proper relation for the clamping at J² and for the subsequent 50 sewing and severing. When the goods is

clamped at J¹ the measured charge J³ may be discharged above such clamp, or when the goods is clamped only at J² the measured charge may be discharged as soon as the clamping is effected at that point upon the 60 goods above such clamp.

K is a sewing and cloth severing device adapted to form two separated seams across the flattened tube, one seam just below the section above the point J² and the other 65 just above the filled bag section. The material is severed between the two seams thus forming the bottom of the bag next to be formed and the top of the filled bag section L below. This filled bag section for such 70 seaming and severing is preferably supported as for instance at M on a jiggling table which is operated by the jiggling device N so as to settle the material in the bag and fill out its bottom portion. This material is also 75 preferably settled before the sewing and severing at the top portion of the section to be filled by compressing the material within such upper portion and this may be done by the pressure device O O. In the preferred method of operating my invention 80 after the lower portion of the bag section has been filled out or the charge settled or after the charge has been deposited in such lower portion it is pulled up and then the 85 upper compressing device O O is operated so as to properly settle or compress or pack the charge within the bag section L. The precise order of these several steps will 90 of course, be carried out to suit the convenience of the operator or to adapt the method to the machine or machines which may be employed in carrying out the method.

I shall state the method in more general terms.

The use and operation of my invention are as follows:

A roll of bag material suitably mounted is preferably drawn forwardly or upwardly between feeding rolls and its two longitudinal edges are stitched together to form a tube which is folded down within itself, the tube or bag material being properly supported, so as to bring the seam inside the tube. At a suitable point the two sides of 100 the descending tube are spread so as to take up the slack and flatten and give proper tension to the tube. The tube is then gripped below the point where it is so spread, preferably by some kind of clamp- 105 110

ing device, and there is preferably a long interval between such clamp and the support of the tube, so that there may be any desired amount of slack or puckering in the tube. This makes it possible to operate the mechanism which makes the seam for the tube and the mechanism which makes the stitching across the tube to form the bag separately and not in synchronism. In other words, the two operations are entirely independent of each other, however they may be carried on, and the bag or tube material between them may be accumulated to any reasonable extent. A measured quantity of material is dropped into the tube and it falls into the lower bag section of the tube, resting against the clamp or the cloth of the tube at a point where its two sides are held together by the clamp. The tube is now stitched across below the clamp and the cloth cut below such stitching so as to form a closed end for such bag section. The clamp now opens and the bag drops to the jiggling table, the material being thus settled or compressed and the bottom of the bag filled out. The bag is jiggled in any desired manner and to any degree to effect the settling of the material. The filled bag section may then be lifted up by a pull on the bag tube and the cloth of the tube about the upper portion of the filling charge is pressed down so as to fill out the upper portion of the bag, compressing the material in it. The tube above such filled bag is then clamped and the next charge of material is dropped into the bag tube and held above the clamp while the two seams are run across the tube at the same time and the material between them is cut and the process continued. Of course, these several steps need not all of them be carried out in the precise order indicated, but with any ordinary form of mechanism, it would be found convenient to proceed substantially as proposed above. It is also obvious that each successive bag could be formed separately, but in the case of employment of mechanism, it is plain that as the top of one bag is completed the bottom of the next should be also completed so that the process becomes continuous.

I claim:

1. The method of producing and filling bag-like packages of material from a roll of fabric which consists in forming from said fabric a tube supporting it so as to leave a depending section, stretching it so as to flatten it, clamping the sides of said flattened section, discharging a measured quantity of material in such tube so that it falls into the portion of the tube above the clamped portion, sewing and severing the tube below the clamped portion so as to form the bottom of the bag, settling or packing the material in such filled section, clamping the material of the tube above the

filled bag section and sewing and severing it so as to form a complete separated filled bag.

2. The method of producing and filling bag-like packages of material from a roll of fabric which consists in forming from said fabric a tube supporting it so as to leave a depending section, stretching it so as to flatten it, clamping the sides of such flattened section, discharging a measured quantity of material into such tube so that it falls into the portion of the tube above the clamped portion, sewing and severing the tube below the clamped portion so as to form the bottom of the bag, jiggling such filled section so as to settle the material therein, pressing the material in the filled section from above to compress it and fill out the upper portion of the bag while the bag is suspended from above, clamping the material of the tube above the filled bag section and sewing and severing it so as to form a complete, separated filled bag.

3. The method of producing and filling bag-like packages of material from a roll of fabric which consists in forming from said fabric a tube supporting it so as to leave a depending section, stretching it so as to flatten it, clamping the sides of such flattened section, discharging a measured quantity of material into such tube so that it falls into the portion of the tube above the clamped portion, sewing and severing the tube below the clamped portion so as to form the bottom of the bag, dropping the filled bag section, jiggling it to settle the material raising the filled bag section, pressing the material in the filled section from above to compress it and fill out the upper portion of the bag, clamping the material of the tube above the filled bag section and sewing and severing it so as to form a complete separated filled bag.

4. The method of producing and filling bag-like packages of material from a roll of fabric which consists in forming from said fabric a tube supporting it so as to leave a depending section, stretching it so as to flatten it, clamping the sides of such flattened section, discharging a measured quantity of material into such tube so that it falls into the portion of the tube above the clamped portion, sewing and severing the tube below the clamped portion so as to form the bottom of the bag, dropping the filled bag section, jiggling it to settle the material, raising the filled bag section, clamping the material of the tube above the filled bag section and sewing and severing it so as to form a complete, separated filled bag.

5. The method of producing and filling bag-like packages of material from a roll of fabric which consists in forming from said fabric a tube supporting it so as to leave a depending section, clamping the sides of

5 said section, discharging a measured quantity of material in such tube so that it falls into the portion of the tube above the clamped portion, sewing and severing the tube below the clamped portion so as to form the bottom of the bag, settling or packing the material in such filled section, clamping the material of the tube above the filled bag section and sewing and severing it so as to form a complete separated filled bag.

6. The method of producing and filling bag-like packages of material from a roll of fabric which consists in forming from 15 said fabric a tube supporting it so as to leave a depending section, clamping the sides of such section, discharging a measured quantity of material into such tube so that it falls into the portion of the tube above the 20 clamped portion, sewing and severing the tube below the clamped portion so as to form the bottom of the bag, dropping the filled bag section, jigging it to settle the material, raising the filled bag section, pressing 25 the material in the filled section from above to compress it and fill out the upper portion of the bag, clamping the material of the tube above the filled bag section and sewing and severing it so as to form a complete separated filled bag.

7. The method of producing and filling bag-like packages of material from a roll of fabric which consists in forming from said fabric a tube supporting it so as to leave a 35 depending section, clamping the sides of such section, discharging a measured quantity of material into such tube so that it falls into the portion of the tube above the clamped portion, sewing and severing the 40 tube below the clamped portion so as to form the bottom of the bag, dropping the filled bag section, jigging it to settle the material, raising the filled bag section, clamping the material of the tube above the 45 filled bag section and sewing and severing it so as to form a complete, separated filled bag.

8. The method of producing and filling bag-like packages of material from a roll of fabric which consists in forming from 50 said fabric a tube supporting it so as to leave a depending section, stretching it, so as to flatten it, clamping the sides of said flattened section, discharging a measured quantity of material in such tube so that it falls into 55 the portion of the tube above the clamped portion, sewing and severing the tube below the clamped portion so as to form the bottom of the bag, settling or packing the material in such filled section, 60 clamping the material of the tube above the filled bag section, discharging another charge of material into such tube so that it falls into the portion of the tube above the clamped portion and sewing and severing 65 the tube so as to simultaneously form the

bottom of the next bag in the series and to form a complete, separated filled bag of the first in the series.

9. The method of producing and filling bag-like packages of material from a roll of fabric which consists in forming from said fabric a tube supporting it so as to leave a depending section, stretching it so as to flatten it, clamping the sides of such flattened section, discharging a measured quantity of material into such tube so that it falls into the portion of the tube above the clamped portion, sewing and severing the tube below the clamped portion, so as to form the bottom of the bag, jigging such filled section so as to settle the material therein, pressing the material in the filled section from above to compress it and fill out the upper portion of the bag, clamping the material of the tube above the filled bag section, discharging another charge of material into such tube so that it falls into the portion of the tube above the clamped portion, and sewing and severing the tube so as to simultaneously form the bottom of the next bag in series and to form a complete separated filled bag of the first in series.

10. The method of producing and filling bag-like packages of material from a roll of fabric which consists in forming from said fabric a tube supporting it so as to leave a depending section, stretching it so as to flatten it, clamping the sides of such flattened section, discharging a measured quantity of material into such tube so that it falls into the portion of the tube above the clamped portion, sewing and severing the tube below the clamped portion so as to form the bottom of the bag, dropping the filled bag section, jigging it to settle the material, raising the filled bag section, clamping the material of the tube above the filled bag section, discharging another charge of material into such tube so that it falls into the portion of the tube above the clamped portion and sewing or severing the tube so as to simultaneously form the bottom of the next bag in series and to form a complete separated filled bag of the first series.

11. The method of producing and filling bag-like packages of material from a roll of fabric which consists in forming from said fabric a tube supporting it so as to leave a depending section, clamping the sides of said section, discharging a measured quantity of material in such tube so that it falls into the portion of the tube above the clamped portion, sewing and severing the tube below the clamped portion so as to form the bottom of the bag, settling or packing the material in such filled section, clamping the material of the tube above the filled bag section, discharging another charge of material into such tube so that it falls into the portion of the tube above the clamped portion, and 130

sewing and severing the tube so as to simultaneously form the bottom of the next bag in series and to form a complete, separated filled bag of the first series.

5 12. The method of producing and filling bag-like packages of material from a roll of fabric which consists in forming from said fabric a tube supporting it so as to leave a depending section, clamping the sides of 10 such section, discharging a measured quantity of material into such tube so that it falls into the portion of the tube above the clamped portion, sewing and severing the tube below the clamped portion so as to form 15 the bottom of the bag, jiggling such filled section so as to settle the material therein, pressing the material in the filled section from above to compress it and fill out the upper portion of the bag, clamping the material of the tube above the filled bag section, discharging another charge of material 20 into such tube so that it falls into the portion of the tube above the clamped portion, and sewing and severing the tube so as to 25 simultaneously form the bottom of the next bag in series and to form a complete, separated filled bag of the first in series.

13. The method of producing and filling bag-like packages of material from a roll of 30 fabric which consists in forming from said fabric a tube supporting it so as to leave a depending section, clamping the sides of such section, discharging a measured quantity of material into such tube so that it falls into the portion of the tube above the clamped portion, sewing and severing the tube below the clamped portion so as to 35 form the bottom of the bag, dropping the filled bag section, jiggling it to settle the material, raising the filled bag section, clamping the material of the tube above the filled bag section, discharging another 40 charge of material into such tube so that it falls into the portion of the tube above the 45 clamped portion and sewing and severing

the tube so as to simultaneously form the bottom of the next bag in series and to form a complete, separated filled bag of the first in series.

14. The method of producing and filling 50 bag like packages of material from a roll of fabric which consists in forming of such fabric a tube feeding separate measured charges of the filling material into the tube, clamping the tube between such charges to 55 keep them separated, running two seams across the tube between the charges severing the tube between the seams to complete one finished bag, then unclamping the tube so as to permit the next charge to drop against 60 the bottom formed by one of the two seams and continuing the operation.

15. The method of producing and filling bag like packages of material which consists in forming a bag tube section, closing 65 one end, discharging the material into the tube through the other end, jiggling the filled bag section from below compressing the material within the bag by pressure from above and closing the upper end of the bag to complete it.

16. The method of producing and filling bag like packages of material from a roll of fabric which consists in forming from 70 said fabric a tube closing one end thereof 75 inserting a charge of filling material through the tube into a bag section of said tube on such closure, jiggling the material from below pressing it into position from above and closing the tube above such 80 charge and severing the filled section from the tube.

In testimony whereof I affix my signature in the presence of two witnesses this 20th day of March 1919.

ADELMER M. BATES.
